UNITED STATES PATENT OFFICE.

ORVILLE E. SAHOLD, OF GLENDALE, CALIFORNIA.

POULTRY-ROOST SUPPORT AND AUTOMATIC DROPPINGS CONVEYER.

Application filed August 17, 1925. Serial No. 50,764.

The present invention relates to certain improvements in chicken houses and particularly to the roost support thereof and the provision of means whereby the droppings may be cleaned automatically.

An important object of the invention is to provide an endless member for receiving the droppings which may be operated to deliver said droppings exteriorly of the chicken house onto a conveyer in order that they may be loaded into a suitable receptacle or wagon.

A further very important object of the invention is to provide a structure of this nature which is exceedingly simple, durable, one which is thoroughly reliable and efficient in operation not likely to easily become out of order, and otherwise well adapted for the purpose for which it is designed.

With the above and numerous other objects in view, as will appear as the description proceeds, the invention resides in the novel features of construction, and in the combination and arrangement of parts as will be hereinafter more fully described and claimed.

In the drawings:—

Figure 1 is a sectional view through one end of the chicken house showing my improvement associated therewith.

Figure 2 is a transverse vertical sectional view through my improved structure.

Figure 3 is a sectional view taken substantially on the line 3—3 of Figure 2 and

Figure 4 is a sectional view taken substantially on the line 4—4 of Figure 2.

Referring to the drawing in detail, it will be seen that 5 designates a stringer which extends along the one wall of the chicken house in any suitable manner and has projecting therefrom at suitable intervals angle iron brackets 6 provided with edge notches 7. A roost 8 is disposed on the angle iron brackets 6 being held in place by screws 9 or other suitable fastening elements which engage in the notches 7 as is clearly shown in Figure 4. A stringer 10 is disposed below the stringer 5 and is cut away longitudinally at the upper and lower inside corners as indicated at 11. Suitable journals 12 are mounted at the ends of the stringer 10 and receive shafts 13 and 14 on each of which is mounted a pair of sprockets 15 engaged with the respective shafts by screws 16 or in any other suitable manner. Chains 17 are trained over the sprockets 15 and certain

links thereof are provided with laterally extending ears 18 to which are bolted cross stringers 19. An endless belt 20 of ducking or coated material forms the droppings catcher and is disposed about the stringers 19 and fixed thereto by screws 21. The width of this belt 20 is such as to overlap the upper run of the chain 17 as is clearly indicated in Figure 2. A strap iron supporting rail 22 is mounted in the top way 11 and supports the upper run of the chain 17. A similar rail 23 is attached to the lower edge of the stringer 10 and extends over the lower way 11 and supports the lower run of the chain 17, it being noted from Figure 2 that the edge of the belt 20 at its lower run extends under this rail 23 thereby eliminating wear thereon.

By referring to Figure 1 it will be seen that the shaft 14 is mounted in any suitable manner exteriorly of the chicken house and a shaft 24 is mounted below the shaft 14 between the chicken house and said shaft 14, and has mounted thereon other sprockets 15 so that the chains after passing over the sprockets on shaft 14 slant inwardly and downwardly. The endless droppings catcher then passes over a roller 25 mounted adjacent the opening 26. At a similar opening 28 in the other end of the housing there are disposed hingedly mounted doors 29. If the housing is divided by partitions, said partitions will also have other doors 29. Any suitable means may be utilized for operating these doors in unison when the endless catcher is being shifted. This endless catcher which I have described in detail may be shifted either manually or by use of an electric motor (not shown) or in any other suitable manner. An elevator 30 is provided at the outer end of the droppings catcher so that when the catcher is shifted, the droppings will fall upon the conveyer in order that they may be elevated to a receptacle, wagon, or the like. It is not necessary that this elevator 30 be used, as the droppings may fall into a suitable receptacle or onto the ground at the bottom of the outer end of the catcher.

As will be appreciated by those skilled in this art, some of the droppings will stick to the belt and I therefore provide positive means for cleaning the belt before its return into the chicken house. This means is illustrated to advantage in Figure 1 wherein the numeral 32 designates a suitable rotary

brush, the bristles of which engage the endless belt after it leaves the sprockets of the shaft 24. A water pipe 33 extends up the outside of the chicken house and has an angular extension 24 for spraying the belt above the brush 32. It is obvious that when the belt is being shifted the water is turned on and the brush 32 is placed in rotation in any suitable manner. When the dirty part of the catcher has been cleaned it will be damp and wet but will be the under run of the catcher in the chicken house and will therefore have an opportunity of thoroughly drying before being brought into actual use. After the catcher has been cleaned, the doors 29 will be closed so as to eliminate any possibility of draft.

It is thought that the construction, operation and advantages of the invention will now be clearly understood without a more detail description thereof. It is desired however, to point out that numerous changes in the details of construction and in the combination and arrangement of parts may be resorted to without departing from the spirit or scope of the invention as herein-after claimed, or sacrificing any of its advantages.

Having thus described my invention what I claim as new is:

1. A droppings catcher mechanism including an endless belt, stringers fixed to the interior surface of the endless belt, chains fixed to the ends of the stringers, sprockets over which said chains are trained, rails for supporting the upper runs of the

chains and the lower runs of the chains, the rail supporting the lower runs of the chains separating the edges of the endless belt from the chains.

2. A droppings catcher mechanism including a pair of spaced longitudinal supporting stringers having their inner upper and lower corners cut away to provide ways at their ends, shafts journaled at the ends of the stringers, sprockets on the shafts, chains trained over the sprockets to move in the ways, a rail in each upper way, a rail below each lower way, cross members connected to the chains, an endless belt fixed to the members and being of sufficient width to overlap the chains.

3. A droppings catcher mechanism including a pair of spaced longitudinal supporting stringers having their inner upper and lower corners cut away to provide ways at their ends, shafts journaled at the ends of the stringers, sprockets on the shafts, chains trained over the sprockets to move in the ways, a rail in each upper way, a rail below each lower way, cross members connected to the chains, an endless belt fixed to the members and being of sufficient width to overlap the chains, the upper rail being adapted to support the upper run of the chains and the lower rail adapted to support the lower runs of the chains and to separate the overlapping edge portion of the belt from the chains.

In testimony whereof I affix my signature.

ORVILLE E. SAHOLT.
